DESIGN FOR A COMBINATION LAMP AND CHAIR OR SIMILAR ARTICLE

Albert A. Granovsky, New York, N. Y.

Application April 6, 1934, Serial No. 51,327

Term of patent 3½ years

To all whom it may concern:

Be it known that I, ALBERT A. GRANOVSKY, a citizen of the United States, residing at New York city, in the county and State of New York, have invented a certain new, original, and ornamental Design for Combination Lamps and Chairs or Similar Articles, of which the following is a specification, reference being had to the accompanying drawing, forming a part thereof, and of which Figure 1 is a perspective view of the combination lamp and chair, as seen from a point at a side and in front of and above the same; and

Fig. 2 is a perspective view of the combination lamp and chair as seen from a point above and directly in front of the same.

The drawing shows a fabric upholstered armchair having lamps set into the body thereof above the arms, and reflective rims around the frosted curved glass windows for the lamps.

I claim:

The ornamental design for a combination lamp and chair or similar article, substantially as shown and described.

ALBERT A. GRANOVSKY.
